CAR COUPLER

Ernst A. Larsson, Mansfield, Ohio, assignor to The
Ohio Brass Company, Mansfield, Ohio, a cor-
poration of New Jersey

Application February 24, 1938, Serial No. 192,290

3 Claims. (Cl. 213—175)

My invention relates to car couplers for mechanically connecting cars and is especially adapted for cars such as are used in mines and about industrial institutions where it is not especially desired to reverse the cars end for end, but where the cars are usually positioned in a certain relation to each other and which position is maintained.

When it is desirable to switch the cars end for end frequently, then an automatic coupler in which the heads are duplicates should be used.

My invention resides in the new and novel construction, combination and relation of the various parts illustrated and disclosed in the accompanying drawing, in which—

Fig. 1 is a top view of one head of my coupler.

Fig. 2 is a top view of another head of my coupler to couple with the head shown in Fig. 1.

Fig. 3 is a side view of Fig. 1.

Fig. 4 is a side view of Fig. 2.

Fig. 5 is a face view of Fig. 1.

Fig. 6 is an enlarged view in longitudinal partial section of the head shown in Fig. 1 and discloses the spring draft gear and normal relation of the parts thereof.

Fig. 7 is a view in longitudinal partial section of portions of two coupled heads to show the relation of the locking portions when in a locked position and under slight tension.

Fig. 8 is a view in longitudinal partial section of parts of two coupled heads showing the relation of the locking portions when the faces of the heads are under compression.

Fig. 9 shows a view in partial longitudinal section of the rear end portion of the spring draft gear when the same is under tension and the spring compressed to its predetermined limit.

In the preferred embodiment of my invention, I make use of two heads A and B adapted to operate with each other and which are secured to the ends of the cars by means of the member 1 which is secured to the tail piece 2.

The coupler head A is provided with a hollow body member 3 and the coupler B is provided with a body member 3' and positioned within each member 3 and 3' is a shoulder 4 against which the draft spring 5 rests. The rear ends of the hollow bodies 3 and 3' are provided with closure means comprising a sleeve 6 which may be of one piece or split and held in position by rivets, bolts, or other means 7. Each part of the split means 6 is provided with a shoulder 8. The tail piece 2 extends through the member 6 and is guided thereby.

The draft gear member 2 is provided with pro-

jecting wings or lugs 9 which are normally spaced from the end face 10 of the member 6 but which engage with the face of the member 6 when the couplers are placed under sufficient compression. The amount of movement allowed is such that the spring 5 will not be compressed to its limit, thus the spring is protected against over compression.

The member 6 is normally placed in contact with the shoulder 6' on the body 3, thus all strain 10 upon the bolts 7 is prevented when the parts 2 and 3 are placed under maximum compression.

The member 2 is, also, provided with a shoulder 11 which is normally spaced from the shoulder 8 of the member 6, but which contacts with the shoulder 8 when the couplers are placed under sufficient tension but the movement permitted is not sufficient to compress the spring 5 to its limit, therefore, the spring 5 is protected against over compression.

The inner end of the member 2 is provided with a sleeve 12 secured in place by the rivet or other means 13. The sleeve 12 engages with one end of the spring 5 and the spacing between the sleeve 12 and the shoulder 14 on the member 2 is equal to the distance between the shoulder 4 on the member 2 and the shoulder 15 on the member 6 and the spacing is such that when the parts are assembled the spring 5 will be compressed to a predetermined value and under normal conditions, that is, when there is no compression or tension of the heads A and B relative to each other, will maintain a separation between the parts 9 and 10 and the parts 8 and 11.

The front end of the coupler head A is provided with a rectangular recess 16 having an enlarged opening forming a so-called bell shaped mouth with bevelled faces 18 which assist in automatically gathering and centering the projecting pin 17 on the companion head B.

The upper wall of the head A adjacent the front end thereof is provided with a slot 19 to receive the pivotally mounted locking latch 20. Projecting upwardly from the upper wall of the head A are spaced lugs 21 having registering through openings to receive the pin 22 for holding the latch 20 in position and upon which the latch pivots. The latch is on an uncoupled head held in its locked position by means of the spring assembly 23 and is moved by the spring to its locking position when two heads are moved to a coupled position.

The latch 20 is provided with a lifting arm 24 having a finger catch 25, and a projecting arm 26 provided with a cam face 27 to engage the face 55

28 on the projecting portion 17 of the cooperating head B.

I have found that it is very essential to so construct and arrange the cam faces 27 and 28 relative to each other and also their cooperation that jar and vibration and relative movement will not tend to cause the latch to creep to the open position as is the case under many conditions where a latch with a cam face is used. In prior constructions using cams the effective portions of the faces 27 and 28 would be so formed and so related that when the latch 20 is moved to its closed position, the result would be to force the faces 29 and 30 of the heads A and B into engagement as shown in Fig. 8 or to merely hold the faces in engagement as in the case of Patent 1,609,444, but as just stated, I find that a latch with a cam operating in that manner has a tendency to creep to its open position allowing the heads 20 to separate even though a spring may be used in an attempt to hold the latch in its locking position. By effective I mean those portions of the bearing faces in engagement.

I, therefore, so construct and relate the effective bearing faces 27 and 28 that the tendency will be for the latch to move or creep further to its locking position or remain in its locking position under operation and this would be in addition to the tendency of the spring 23 to hold the latch in the locking position. To bring about this condition, all radii of the face 27 and of the face 28 are normal to such faces and emanate from points along a common axis X when the coupler faces 29 and 30 abut, and which axis is spaced from the pivotal axis Y of the latch 20 but preferably located within the circumference of the pin 22 and parallel to the axis Y.

This relative arrangement of the said axes produces a moment tending to rotate the latch about its axis of rotation in its locking direction when the bearing faces are under draft.

In Figs. 6 and 8 the axis X is shown below and to the left of the pivotal center Y but within the cross-section area of the pin 22 and with the radii C and D emanating from a point along the axis X. In Fig. 8 the surfaces 29 and 30 of the heads A and B are in an abutting relation but when the heads are under tension with the latch 20 in locking position the faces 27 and 28 will contact as shown in Fig. 7, but the faces 29 and 30 of the heads A and B will be spaced.

When the couplers are in coupled relation as shown in Fig. 7 and forces applied to the latch 20 tending to move it to its unlocked position either manually or through creepage the latch will tend to pivot about the axis Y but the axis X of the face 27 of the latch will tend to move on a circle 31 the center of which is axis Y, therefore, it will be evident that the tip 32 of the latch 20 will tend to move along a path represented by the dotted line 33, the radius of which is E (Fig. 8), and the tendency therefore will be, when the faces 27 and 28 are in contact as in Fig. 7, to force the heads A and B in closer coupled relation, thus eliminating the space between the faces 29 and 30. The result of the above construction will be for the lock to move more to the locking position and not to the unlocking position under normal operation.

It will be noted in Fig. 8 that when the faces 29 and 30 contact that the point 32 on the cam face 27 will just miss engagement with the upper edge of the cam face 28 when the latch is moved to its open and closed positions.

What has been described with respect to the

movement of the point 32 on the cam face 28 is also true of other points on the cam face 27, that is, they will follow an arc of a circle emanating from the center Y.

In my construction I have sacrificed the so-called tight-lock feature in which the faces 29 and 30 would engage thus preventing slack, for the more important feature of safely coupled heads under normal operation. 5

I find that by forming the faces 27 and 28 10 as previously explained with the axis X not too far spaced from the axis Y that the heads will not have a detrimental amount of slack, but with my improved construction it is necessary to have sufficient slack to permit the point 32 on the 15 cam to clear the tongue 17 on the other head as my construction produces an actual interlock of the latch and tongue 17 when the heads are under draft and the greater the distance between the axes X and Y in substantially the direction 20 shown the greater the interlock will be and hence the greater slack required to permit movement of the latch in coupling and uncoupling and, also, greater will be the resistance to uncoupling.

The rectangular portion 34 of the head B corresponds to the rectangular opening 16 of the head A and is made a reasonably easy sliding fit therewith or with a small clearance so as to eliminate to a reasonable degree relative transverse movement of the heads A and B and twisting motion. 25

It will be evident that when it is desired to intentionally uncouple the heads that the faces 29 and 30 should be in contact as shown in Fig. 8 or substantially so in order to easily operate the 35 latch 20 to its unlocking position otherwise if the pull in tension upon the coupler heads is sufficient it may be impossible to move the latch 20 to the uncoupling position.

It is not necessary that the faces 29 and 30 40 should engage, as other means for preventing relative longitudinal movement of the heads beyond a predetermined point under compression forces may be used.

While I have shown the radii C and D as having 45 a common center, the center of radius D may be the center Y but the center of radius C should be so spaced from center Y as to effect a clamping tendency when the latch 20 tends to move 50 to its unlatching position. 50

Modifications will suggest themselves to those skilled in the art; therefore, I wish to be limited only by my claims.

I claim:

1. A car coupler comprising a pair of heads, each head comprising a body, means on each head to attach it to a car end, one head having a rectangular opening at the front end of the body and the other end having a projecting tongue to enter the said opening, the tongue having substantially the same cross-sectional shape and size as that of the opening to prevent relative transverse and rotational movement of the heads, the said opening having a flaring mouth for gathering in the said tongue, the tongue provided with a notch having an extended bearing face, a latch associated with the body of the first said head and a transversely disposed pin associated with the body and upon which the latch is pivotally mounted, the latch provided with a lug projecting through an opening provided in the wall of the body and into the said opening therein, the said lug having an extended bearing face to engage with the first said bearing face to hold the heads in coupled relation, the said bearing 75

faces being formed in the arc of a circle having a common axis of curvature, the axis of curvature of the bearing faces being spaced from the pivotal axis of the pin a distance not greater than 5 the radius of the said pin and extending parallel to the axis thereof, intermediate the pivotal axis and the longitudinal axis of the coupler heads and forward of the pivotal axis whereby when the heads are in draft the bearing face on the latch 10 will be in engagement with the bearing face on the companion head and subject to a locking moment preventing the latch moving to its unlocking position about the pivotal axis, the bearing faces being spaced apart when the heads are 15 in buff whereby the latch is manually movable into and out of its locking position without engaging the bearing face of the said notch, further when the heads are in draft the latch will tend to automatically move in the direction of 20 its locking position.

2. A car coupler comprising a pair of cooperating heads of different construction, each head comprising a body having means to attach the body to a car end, one head having an opening at 25 its forward end and the other head having a projection adapted to enter the opening, each head having a buffing face adapted to contact with the face on the cooperating head, means to prevent the coupler heads rotating relative to each other 30 and to prevent relative transverse movement of the heads, the said projection provided with a notch having an arcuate bearing face, a latch associated with the body of the cooperating head and having an arcuate bearing face to cooperate 35 with the bearing face of the notch on the said projection to hold the couplers in coupled relation while under draft, a pin associated with the said cooperating head and upon which the latch is pivotally mounted, the radii of the bearing faces having a common axis which extends 40 longitudinally through the pin at a point between the pivotal axis of the pin and the central

longitudinal axis of the heads and spaced from and parallel to the pivotal axis of the said pin whereby the pulling forces between the bearing faces when the heads are in draft will be centered along the axis of curvature and thereby create a 5 turning movement tending to rotate the latch in its locking direction about its pivotal axis.

3. A car coupler comprising a pair of coupling heads of different construction, each head comprising a body having means at one end to attach 10 it to a car body, one head having at the other end an opening and the other head having at its other end a projection adapted to enter the opening, each head having a bumping face adapted to contact with the face of the mating coupler when the 15 heads are brought together in buff, means to prevent the coupler heads rotating relative to each other, the said projection provided with transverse means having an arcuate bearing face of extended area, a latch pivoted on the body of the 20 said mating head and having an arcuate bearing face of extended area arranged to cooperate with the other bearing face to hold the couplers in coupled relation, the said bearing faces being spaced apart when the bumper faces are together and 25 the bumper faces spaced when the bearing faces are in engagement, the radii of the bearing faces having a common axis of curvature which is spaced from and parallel to the pivotal axis of the latch and the said axis of curvature positioned 30 intermediate the pivotal axis and the central longitudinal axis of the heads and toward the front end of the head on which the latch is mounted relative to the pivotal axis intermediate the said face and the pivotal axis whereby turning moments will be effected tending to move the latch in the direction of its locking position when the heads are in draft and yielding means to move the latch to its locking position when the heads 35 are in buff. 40
